E. J. SCHORDENE

INDICATING PLUG FUSE FOR ELECTRIC CIRCUITS

Filed Feb. 2, 1926

INVENTOR
Fred J. Schordene
ATTORNEY
Rutan & Pollock

UNITED STATES PATENT OFFICE.

FRED J. SCHORDENE, OF PATCHOGUE, NEW YORK.

INDICATING PLUG FUSE FOR ELECTRIC CIRCUITS.

Application filed February 2, 1926. Serial No. 85,495.

This invention relates to fuse plugs for electrical circuits, and particularly an indicating plug, which shall give visible warning of the blowing out of the fuse element contained therein:

A further object is to provide an article conforming to general practice in respect to the form, and proportions of the outside threaded shell members, which may be inserted in fuse sockets such as may be found in the usual electric circuits.

For further comprehension of the invention, and of the objects and advantages thereof, reference will be had to the following description and accompanying drawing, and to the appended claims in which the various novel features of the invention are more particularly set forth.

Fig. 1 of the drawing shows an exterior side elevation of a device constructed according to this invention.

Fig. 2 shows a central vertical sectional view taken on the line 2—2 of Fig. 1.

Fig. 3 shows a bottom view of the device.

Fig. 4 shows a horizontal sectional view taken on the line 4—4 of Fig. 2.

Fig. 5 shows a modified form of this invention.

Fig. 6 shows a further modification.

Fig. 7 shows a horizontal sectional view taken on the line 7—7 of Fig. 6.

Fig. 8 shows a horizontal sectional view taken on the line 8—8 of Fig. 6.

Fig. 9 shows a similar construction as Fig. 2, but of slightly modified form.

Fig. 10 shows an enlarged fragmentary view of the clamp for the lower end of the fuse 18, as shown in Fig. 9. Fig. 11 shows an enlarged fragmentary view of the clamping means for the upper end of the fuse 18, as shown in Fig. 9.

Referring to the form of the invention shown in Fig. 2, a fuse element 18, connects from the central contact 14 through a groove in the insulation member 12 to the contact shell 10. A conductor disk 35 has a projection 36 extending thru the socket 11, and making contact therewith. A connection wire 19, in a groove of the insulation member 12, has its upper end soldered to the projection 36, and its lower end to the shell 10.

Referring to the form shown in Fig. 9, a contact shell 10, of the customary threaded construction to fit into standard electrical sockets, is mounted on an insulating element 12, preferably of porcelain, which has a cen-

tral threaded aperture engaging a socket 11 adapted to support an indicating electric lamp 21, having an upper threaded portion 22, and at the uppermost extremity a contact pole 23. Co-actable with this pole 23 is another pole 15 on the lower end of a connecting element 13, which is provided at its uppermost portion with a contact 14, which is adapted to connect with the customary central contact of an electric socket, and is formed with threads 14^a to engage the connecting element 13. Clamped between the top of element 13 and the contact 14 is a fuse element 18 of suitable material which passes in a channel 12^a of the insulating material 12, to a point near the contact shell 10, and is clamped thereto by means of a toothed lever 10^a pivotally mounted to the shell, and forced by spring 10^b, against a toothed stationary portion 10^c, integral with the contact shell. An insulation washer 16 of semi-spherical form is arranged to cover the end of the plug so as to cover the channel 12^a, and is held down by the contact 14, and by having its outer edge clamped between the shell and the insulation member 12.

The bottom of the connecting element 13 is insulated from the disk 35 by the insulation piece 17, the upper end of wire 19, is soldered to a conductor disk 35, specifically the projection thereon 36 which makes contact with the socket 11 which in turn contacts with socket 22, and said wire may be a fusible wire of higher melting point than the fuse element 18, and this wire 19 is clamped at its lower end by the contact shell and soldered thereto. The member 12 has extending downward and flaring outward a rim to form a lamp shade 25, which has a protecting wire mesh 24 secured thereto.

It will be seen, that normally with the fuse 18 intact, current passing thru the plug will follow the course of least resistance which is through the fuse 18, and the lamp circuit being of high resistance will result in the lamp being unlit, but should the fuse 18 blow, the current will then have to pass through the lamp, illuminating the same, continue through the socket 11, the socket 22, and thence through the wire 19 to the outer shell. The lamp, now being illuminated would indicate that the fuse was blown and must be replaced.

In the form of the invention shown in Fig. 5, the fuse 18 makes circuit from the contact point 14 to the shell thru a passage in the

member 12, while wire 19 connects the socket 22 to the shell in a direct path, and the top of the fuse is provided with a large insulation washer 26.

- 5 In the form of the invention illustrated in Figs. 6, 7, and 8, the insulation member 12' is formed with two longitudinal chambers, one of these chambers being on the inner portion, which houses contact spring 30 bearing 10 against the socket 11, while the other chamber being on the outer portion, housing contact spring 31 which bears against the contact shell 10, the springs 30 and 31 being electrically connected by means of the wire 19^a.
- 15 The connection element 13 is insulated from contact with undesirable parts, by the insulation washers 17^b, 17^c, 17^d, and 17^e. The fuse element 18^a at its top is clamped to the connection element 13 by means of part 14^b, 20 spirals around, and at the bottom is soldered to the clamping rim 32, which also clamps the semi-spherical washer 16, and the flat washer 16^a. The part 14^b is removably fastened to connecting element 13, and upon the 25 removal of this part 14^b, the top semi-spherical washer 16, the fuse 18^a, and the washer 16^a, together with the rim 32 are removable, thereby allowing a complete replacement of this portion. It is readily seen that when a 30 fuse 18^a blows, the entire portions may be replaced with a new fuse contained therein.

The electrical circuits in this modification are similar to those of the above modifications. One circuit exists from the top contact end of 13, through the fuse 18^a, thereafter to the circular rim 32, which makes contact with the shell, and the other circuit extends from the top contact end of 13, to the bottom contact 15, thence to the lamp 40 contact 23, thru the lamp filament, to the socket 11, thereafter to contact spring 30, thru wire 19^a, contact spring 31, and finally to the shell 10.

While I have illustrated and described my 45 invention with some degree of particularity, I realize that in practice various alterations therein may be made, I therefore reserve the right and privilege of changing the form of the details of construction or otherwise altering 50 the arrangement of the correlated parts without departing from the spirit or the scope of the appended claims.

Having thus described my invention, what I claim as new and desire to secure by 55 United States Letters Patent is:—

1. In a fuse plug of the type described, a supporting insulation member provided with an outer contact shell, and an inner lamp socket, said insulation member having a longitudinal groove on the inner wall, and another longitudinal groove on the outer wall, a spring contact in said inner groove bearing against said lamp socket, a spring contact in said outer groove bearing against said contact shell, and a wire electrically connecting said two spring contacts. 60

2. In a plug fuse of the class described, a threaded shell of conductive material, a threaded socket supported therein by means of an annular rim having its outer edges 70 crimped within the walls of the said shell, and current connecting means between the said shell and the said socket, a connecting element extending from the interior of the said socket to the exterior of the said shell 75 and insulated from the said members, and a strip of suitable fuse material connected to the said element and to the said shell, and the space surrounding the said fuse packed with nonconducting material, an electric 80 bulb with suitable stem inserted within the said socket and a protective shade member having a mesh covering thereon to shield the said bulb, substantially as shown and described. 85

3. In a plug fuse of the class described, a threaded shell of electric conductive material, a socket of like material supported centrally therein and in electrical connection therewith, a disk of insulating material secured within the said shell at its upper extremity and acting as a closure therefor, the said disk perforated and having an electric connecting member passing therethrough, and the said connecting member extending 95 through the base of the said socket and insulated therefrom, and a fuse element attached to the said connecting member at one end, and at the other to the aforesaid shell, and the lower edges of the said shell crimped 100 around an annular member which serves as a closure for the face of the said shell, and an electric bulb having its stem inserted within the said socket and its contact point engaging the first mentioned connecting 105 member, substantially as shown and described.

In testimony whereof I have affixed my signature.

FRED J. SCHORDENE.
